(57) **CLAIM**

The ornamental design for a multi-function tool, as shown and described.

DESCRIPTION

The present invention relates generally to tools and painter's tools, and, more specifically, to a multi-function tool.

FIG. 1 is a perspective view of a preferred embodiment of a multi-function tool;

FIG. 2 is a side view of a preferred embodiment of a multi-function tool;

FIG. 3 is a top view of a preferred embodiment of a multi-function tool;

FIG. 4 is a side view of an embodiment of a multi-function tool;

FIG. 5 is a bottom view of a preferred embodiment of a multi-function tool;

FIG. 6 is a rear view of an embodiment of a multi-function tool; and,

FIG. 7 is a front view of a preferred embodiment of a multi-function tool.
